UNITED STATES PATENT OFFICE

ERVIN ADAMS, OF MOUNT CARMEL, PENNSYLVANIA, ASSIGNOR TO HENRY W. BRECKER, OF MOUNT CARMEL, PENNSYLVANIA

FUSIBLE ATTACHMENT PLUG

Application filed May 9, 1931. Serial No. 536,253.

This invention relates to fusible attachment plugs and has for an object to provide a plug for attaching various electrical appliances, such as radios, electric irons, extension lamps, and the like, to convenient sockets, the plug being adapted to completely house a fuse of a capacity sufficient to protect the particular appliance in use, and being composed of sections which may be 10 easily and quickly disassembled to replace a blownout fuse.

A further object is to provide a fusible attachment plug in which tight connections are maintained at all times between the terminals carried by the sections, so that the device 15 will withstand severe conditions of service.

A still further object is to provide a fusible attachment plug which will receive standard fuses of various capacities and will 20 include telescopic sections forming a complete closure around the fuse while, at the same time, being capable of being quickly withdrawn from each other to expose the fuse for replacement by simply unscrewing 25 a single collar.

With the above and other objects in view the invention resides in certain novel details of construction and combinations of parts hereinafter fully described and claimed, it 30 being understood that various modifications may be resorted to within the scope of the appended claims without departing from the spirit or sacrificing any of the advantages of the invention.

35 In the accompanying drawing forming part of this specification,

Figure 1 is a perspective view of a fusible attachment plug constructed in accordance with my invention,

40 Fig. 2 is an enlarged longitudinal sectional view through the plug, and

Fig. 3 is a cross sectional view taken on the line 3—3 of Fig. 2.

Referring now to the drawing in which 45 like characters of reference designate similar parts in the various views, the device is shown to comprise a pair of cylindrical shells 10 and 11, each having an open end, as shown best in Fig. 2. The shells, opposite the open 50 ends thereof, are provided with end walls 12

and 13, respectively, which are of greater thickness than the side walls of the shells to provide mountings for the electric terminals. The inner shell 11 is of sufficient diameter to telescope snugly into the outer shell 10. A flanged collar 14 is threaded onto the open end of the outer shell, as shown at 15, and overlaps the end wall of the inner shell to unite the shells. Preferably, the collar is countersunk in both shells to provide a smooth, continuous exterior surface for the plug. The shells and collar are preferably formed of bakelite or other suitable insulating material.

The inner shell 11 is uniformly reduced 65 at the inner end of the bore thereof to provide a cylindrical chamber 16 in which is permanently mounted a threaded metal socket 17 into which may be screwed a standard fuse plug 18 of the usual type. The metal socket 17 is preferably attached to the inner face of the end wall of the shell 11 by means of screws 19 arranged in an annular series around a central boss 20 which projects from said inner face.

The end wall of the outer shell 10 is provided with a pair of slots 21 to receive the prongs of the attaching plug of whatever electrical device the fusible attachment plug is to be used with, there being spring tongues 22 in the slots permanently secured in place by screws 23, these tongues being adapted to clamp said prongs in the slots in the usual and well-known manner.

The end wall 13 of the inner shell 11 is preferably provided centrally with a countersink 24 in which is bolted, as shown at 25, a pair of prongs 26 adapted to be received in the slots of an electrical socket, such as a wall socket, floor socket, or electric fixture socket, 90 from which the electrical appliance is to be supplied with current.

To electrically connect the fuse in circuit with the prongs 26 and spring tongues 22, the outer shell 12 is provided with a pair 95 of substantially L-shaped metal leaves 28, one leg of each leaf being exposed and extending longitudinally along the inner face of the bore of the shell, and the other leg being directed inwardly through the end wall of 100

the shell and attached underneath the secured ends of the tongues 22 by means of the screws 23 which mount said tongues.

Likewise, the inner shell 11 is provided with a pair of L-shaped leaves 29, one leg of each leaf being exposed exteriorly upon the outer surface of the shell and preferably being countersunk therein and so arranged as to have wiping contact with the corresponding legs of the metal leaves carried by the outer shell 10. It will be observed that one of the leaves 29 has one leg thereof directed inwardly to extend along the inner face of the end wall of the inner shell 11 and is secured thereto by means of one of the above-mentioned bolts 25 which attaches one of the prongs 26 to the shell. The other leaf 29 is considerably shorter than the first-mentioned leaf 29 and has one leg thereof passed through the wall of the inner shell at a point substantially midway between the ends of the shell, the leaf terminating in a lip 30 which is countersunk in the wall of the bore of the shell and frictionally bears against the above-mentioned metal screw socket 17.

To complete the electrical connection, a substantially Z-shaped leaf 31 has one leg secured to the inner face of the end wall of the inner shell 11 by means of the bolt 25 which attaches the adjacent prong 26 to the shell, the opposite terminal of the leaf being resilient and extending obliquely across the above-mentioned boss 20 into the socket 17 and frictionally engaging the center terminal of the fuse plug 18.

By referring to Fig. 2, electrical connections may be traced from the left prong 26 through the bolt 25, leaf 29, leaf 28, and spring tongue 22 on the left side of the device, as shown in Fig. 2. On the right side of the illustration of the device as shown in Fig. 2, electrical connections may be traced through the prong 26, bolt 25, Z-shaped leaf 31, fusible element 32 of the fuse plug 18, metal screw socket 17, leaf 29, leaf 28, and spring tongue 22.

By now referring to Fig. 3, it will be seen that to prevent relative rotation of the shells, preferably the outer shell is provided on the inner face of the bore thereof with a longitudinal rib 33 which engages in a corresponding longitudinal slot 34 formed on the outer surface of the inner shell 11, as best shown in Fig. 3.

From the above description it will be observed that both shells may be detached from each other by simply unscrewing a single collar 14 to expose the fuse plug 18 for replacement when blown. It will be further observed that the fuse plug is completely housed on all sides by the shells. It will still further be observed that the L-shaped leaves forming the terminals, as above described, have wiping contact with each other so that positive electrical connections will be maintained at

all times under the most severe conditions of service. It will further be pointed out that said leaves overlap each other sufficiently to insure adequate electrical connections therebetween at all times.

In operation, of course, a fuse plug 18 of predetermined capacity is always used to protect the particular electrical apparatus being used. For example, it is desirable at times to employ a three-ampere fuse, at other times a five or six ampere, while still again it may be necessary to use a fuse plug of still greater capacity, according to the amount of current which the particular appliance draws. It will be observed that the bore of the inner shell is of sufficient diameter to permit of the fuse plug being screwed into and out of the metal screw socket 17 after the shells have been disassembled.

Having thus described the invention, I claim:

1. A fusible attachment plug comprising telescoped shells detachably secured together, a metal screw socket carried by one of the shells for receiving a standard fuse plug, prongs carried by one of the shells, spring tongues carried by the other shell in slots formed in the shell, overlapping leaves carried by the shells having wiping contact with each other for electrically connecting the prongs and tongues in series with said socket, and a spring tongue carried by one of the shells and projecting into said socket for connecting the center terminal of the fuse plug with one of said prongs.

2. A fusible attachment plug comprising telescoped shells removably secured together in non-rotatable relationship, overlapping spring leaves forming electrical terminals having wiping contact with each other and carried by respective shells, a metal screw socket carried by one of the shells for removably receiving a standard fuse plug, a spring tongue carried by the last-named shell projecting into the socket, prongs carried by one of the shells, and springs tongues carried by the other shell, the prongs and shells being electrically connected in series with said socket by means of said overlapping spring leaves and the first-named spring tongue.

3. A fusible attachment plug comprising telescoped shells having a longitudinal tongue and groove connection to prevent relative rotation, a collar removably secured to one of the shells and overlapping the end of the other shell to confine the shells together, a fuse plug housed completely by the shells and removably secured to one of the shells, prongs carried by one of the shells, there being slots in the other shell having spring tongues concealed therein, and means electrically connecting the fuse plug in series with the prongs and tongues.

4. A fusible attachment plug comprising telescoped shells each having one end closed

and the opposite end open, the open end of each shell being turned toward the closed end of the opposite shell, a collar threaded on the open end of one shell and overlapping the closed end of the other shell to removably secure the shells together, a fuse plug housed completely by the shells and removably secured to one of the shells, prongs carried by one of the shells, there being slots in the other shell, spring tongues confined in said slots, and means electrically connecting the fuse plug in series with the prongs and tongues.

5. A fusible attachment plug comprising telescoped shells, means securing the shells together, means preventing relative rotation of the shells, prongs carried by the inner shell, there being slots in the outer shell, spring tongues in said slots, pairs of L-shaped leaves carried by the shells having wiping contact

10 with each other, one pair of said leaves electrically connecting the prong and corresponding tongue on one side of each shell together, a metal screw socket carried by the inner shell adapted to receive a standard fuse plug, the

15 other pair of L-shaped leaves electrically connecting the socket with the remaining spring tongue on the opposite side of the outer shell, and a metal leaf electrically connected to the remaining prong carried by the inner shell

20 and extending into the screw socket for contact with the center terminal of said fuse plug.
